UNITED STATES PATENT OFFICE.

ANDREW J. BRAUN AND HERMAN G. HOFFMAN, OF ATCHISON, KANSAS.

COMBINATION-LOCK.

1,366,868.

Specification of Letters Patent. Patented Jan. 25, 1921.

Application filed May 11, 1920. Serial No. 380,451.

To all whom it may concern:

Be it known that we, ANDREW J. BRAUN and HERMAN G. HOFFMAN, citizens of the United States, residing at Atchison, in the 5 county of Atchison, State of Kansas, have invented certain new and useful Improvements in Combination-Locks; and we do hereby declare the following to be a full, clear, and exact description of the invention, such as will enable others skilled in the art to which it appertains to make and use the same.

This invention relates to locks, and more especially to those adapted for application 15 to a valve; and the object of the same is to control the operation of a valve in a gasoline supply pipe to the engine of a motor vehicle by means of a permutation lock.

The lock is operated by a dial and knob 20 mounted on the dash, and when the tumblers have been properly set a button on the dash may be turned to open the valve and permit the gasoline to flow. When the driver leaves his car he has but to turn the button to close 25 the valve and then spin the knob to lock the valve closed, and an unauthorized person not knowing the combination will therefore find it impossible to set the lock so as to again open the valve and supply 30 gasoline to run the engine. One feature of the invention consists in mounting the structure within a casing which is automatically locked from the inside by the turning of the shaft which closes the valve, whereby 35 it will be impossible for an unauthorized person to gain entrance to the casing, and in fact, the owner cannot do so without first unlocking the structure.

Details are set forth below and shown in 40 the drawings wherein:

Figure 1 is a vertical section through this device, showing in outline its connection with the tank and engine, and the mounting of its controls on the dash. This view shows 45 the key in dotted lines in its unlocked position.

Fig. 2 is a plan view partly in horizontal section, with the upper part of the casing removed.

50 Fig. 3 shows a front elevation and a side elevation of one of the cams, and Fig. 4 shows a front elevation and a side elevation of one of the tumblers.

Fig. 5 is a section on the line 5—5 of Fig. 1, showing how the top of the casing is engaged with the lower part thereof. 55

Fig. 6 is a section on the line 6—6 of Fig. 1 showing how the top of the casing is hooked to the lower part when the valve is closed. 60

Fig. 7 is a sectional detail on the line 7—7 of Fig. 5.

A gasoline supply pipe 1 leads from a tank indicated at T in Fig. 1 through a valve V, and from this valve a second pipe 2 leads 65 to the carburetor and engine as indicated at E. On the dash D of the machine is mounted a rotary button B and a knob K, and their stems are connected through gears 3 and 4 with a shaft 5 which leads to and operates 70 the valve, and a shaft 6 having a pinion 7 meshing with another pinion 8 on the lock mechanism described below. Said mechanism and valve are mounted within a casing which by preference is bolted to the engine 75 near the carburetor under the hood, and the shafts which lead to the controls on the dash must usually turn some corners as shown, because the controls are considerably higher than this device as a whole. 80

A strong metal casing consists of a lower part or base 10 closed at one end by a disk 11 and having pins 12 thereon projecting inward, and an upper part 13 having internal lugs 14 with perforations to engage said 85 pins. These parts or members of the casing are substantially semi-cylindrical and their other ends are closed as shown at 15 and have registering notches 16 which coact to 90 form bearings for the shafts 5 and 6 referred to, and also these parts have outstanding perforated ears 17 to receive bolts whereby the parts are held together and the whole casing supported at some appropriate point 95 on the frame of the machine or on the engine casing.

Internally at their rear ends the parts also have lugs 18 adapted to be simultaneously engaged by an S-shaped element or double hook 19 which is fast on the valve shaft 5. 100 The shape of this hook is such that when the shaft is turned to close the valve, the hook engages the lugs 18 so that not even the owner can separate the parts of the casing without first turning this shaft a quarter 105 revolution to open the valve; and, as will be

explained, the lock is adapted to prevent such turning of the valve shaft until it has been properly set.

Suitably supported within the lower part 5 of the casing is a core 20 fixed around the valve shaft 5 and having peripheral grooves in which are mounted tumblers 21, 22, and 23 (and others if desired) the last-named being carried at the mouth of a cup 24 whose 10 bottom incloses the end of the core, loosely surrounds the shaft 5, and carries the pinion 8. The tumbler 21 is shown in Fig. 4 provided with a number of holes 25 into which may be selectively set pins 26 which are 15 threaded for this purpose, and by changing these pins the combination can be changed. The turning of the cup and its tumbler first in one direction and then in the other direction causes its pin to strike a pin on the 20 next tumbler and the latter has a second pin on the other side which strikes the pin on the tumbler 21 (and so on if there are more than three tumblers), and by this means the tumblers are successively set until their 25 notches 27 stand in alinement above a key 28 which lies in a channel 29 along the top of the core. This is the well known action of a permutation lock as set by the manipulation of its knob, and well understood.

30 Fast on the valve shaft 5 at opposite ends of the core are cams 30 and 31, the latter being within the cup 24. As seen in Fig. 3, each cam is a disk notched out at one edge to produce a cam face 32 extending for 90° 35 around the periphery of the disk and having shoulders 33 and 34 at its extremities. The key 28 is long enough to extend through these notches in both cams, and the latter are set on the shaft 5 in such relation to the 40 valve that when the key lies against the shoulder 33 at the low end of the cam face 32 the valve is closed, but when the shaft is turned for a quarter revolution to move the shoulder 34 against the key, the valve is 45 opened. This movement, however, causes the rise of the key because of the rise of the cam face, and obviously the key can only rise when the notches 27 in all the tumblers stand directly above it. On the other hand, 50 when the shaft 5 is turned in the other direction to close the valve, the cam faces 32 permit the key to drop back into the channel 29 and by spinning the knob K the tumblers 55 can be turned to leave the permutation lock closed and locked.

Thus it will be seen that the motorist whose car is equipped with this device can very quickly turn off the gas valve and lock it closed, and can then leave his car with the 60 assurance that no one can turn on the gasoline without knowing the combination. Also the rotation of the button B which closed the valve turns the double hook 19 into engagement with both lugs 18, so that the parts 65 of the casing are locked against separation

until the permutation is again unlocked—hence no one can even pry open the casing and get at the valve V. When he returns to his car, he manipulates the knob K to set the tumblers properly, and then turns the 70 button to open the valve as has been explained. From time to time the screw pins 26 can be changed in the holes 25 in one or more of the tumblers, so as to change the combination, especially when the car passes 75 to the next owner.

It might be stated in conclusion that, although the valve is herein described as inserted in a gasoline supply line and the controls as mounted on a motor vehicle dash, 80 it is quite obvious that this structure is applicable to valves or similar members in other lines, and it is only necessary that the controls shall be within reach of the operator. This suggestion is particularly applicable to the use of a two-part casing 85 inclosing the valve and lock mechanism, and its parts hooked together by the turning of the valve shaft so as to prevent an unauthorized person from forcibly gaining entrance 90 to the mechanism without first properly setting the lock. When the hook is thrown to a horizontal, the bolts can be removed from the perforated ears and the upper part 13 of the casing lifted at its rear end and then 95 slid back so that its perforated lugs disengage the pins 12.

What is claimed is:

1. In a valve lock, the combination with a valve and its operating shaft, and a lock 100 mechanism therefor and its operating shaft; of a two-part casing inclosing said valve and mechanism and through which casing said shafts project, lugs in said parts, and a double hook fast on the valve shaft and 105 turned by it to engage said lugs when the shaft is turned to close the valve.

2. In a valve lock, the combination with a valve and its operating shaft, and a lock mechanism therefor and its operating shaft; 110 of a casing composed of upper and lower semi-cylindrical parts, their inner ends being closed and having registering notches through which said shafts project, these ends also having internal lugs, the opposite 115 end of the lower part being closed by a disk having internal pins and the corresponding end of the upper part having internal perforated lugs to engage said pins, and a double hook fast on the valve shaft and 120 turned by it to engage said lugs when the shaft is turned to close the valve.

3. In a valve lock, the combination with the valve, a shaft leading therefrom to a control button, a permutation lock for preventing or permitting the turning of said shaft, and a lock-shaft leading therefrom to its control knob; of a two-part casing 125 inclosing the valve and lock and from which casing said shafts project, means for hook- 130

ing the parts of the casing together at one end, ears on said parts having registering perforations for fastening bolts, internal lugs near the other ends of said parts, and a 5 double hook fast on the valve shaft within the casing and turned into engagement with said lugs when the valve is closed.

4. In a structure of the class described, the combination with a valve, its control 10 shaft, and a pair of disks fast thereon and each having a 90° peripheral cam with shoulders at its ends; of a permutation lock including a core loose on the shaft between said disks and having a channel, a key loose 15 in said channel and extending over the cam

faces, a series of annular tumblers surrounding the core and key and each having an internal notch and coacting pins, a cup whose mouth is attached to one tumbler and whose bottom loosely surrounds said shaft 20 and carries a pinion, and an operating shaft having a pinion engaging with the pinion of the cup.

In testimony whereof, we affix our signatures, in the presence of two witnesses.
